UNITED STATES PATENT OFFICE.

ERNEST STEVENS, OF PHILADELPHIA, PENNSYLVANIA.

DESIGN FOR AN INHALER.

SPECIFICATION forming part of Design No. 32,151, dated January 30, 1900.

Application filed October 13, 1899. Serial No. 733,544. Term of patent 7 years.

To all whom it may concern:

Be it known that I, ERNEST STEVENS, a subject of the Queen of England, residing at Philadelphia, in the county of Philadelphia, State of Pennsylvania, have invented and produced a new and original Design for an Inhaler, of which the following is a specification.

In the accompanying drawing, which forms a part of this specification, my inhaler is illustrated by a perspective view.

Referring particularly to the said drawing, A represents the mouthpiece, which, starting at the oval rim a, gradually curves to unite with the cylindrical tube or body B, which is in two parts united in its central portion and having a raised band c, as shown. At each end of the cylindrical portion are the raised bands d d, roughened or milled in the manner illustrated.

The nose-piece C, starting at the central aperture b, is flattened somewhat and curved, as shown, and gradually increases in diameter until it merges into the cylindrical tube or body B at the intersection of the roughened or milled band d. The aperture in the mouthpiece is tapered or reamed out, as illustrated in the drawing.

Having fully described my invention, what I claim is—

The design for an inhaler as herein shown and described.

In witness whereof I have hereunto affixed my signature, this 31st day of August, 1899, in the presence of two witnesses.

ERNEST STEVENS.
